UNITED STATES PATENT OFFICE.

PAGET HIGGS, OF NEW YORK, N. Y.

DYNAMO-ELECTRIC MACHINE.

SPECIFICATION forming part of Letters Patent No. 242,644, dated June 7, 1881.

Application filed March 3, 1881. (No model.)

To all whom it may concern:

Be it known that I, PAGET HIGGS, a citizen of Great Britain, residing in the city of New York, in the county and State of New York, have invented certain Improvements in Dynamo-Electric Machines, and in the method of working them, of which the following is a specification.

My improvement relates to that class of magneto-electric machines in which the electric current is induced in the coils of an armature by means of electro-magnets, and which are distinguished from those in which permanent magnets are used by the title "dynamo-electric machines;" and the invention is applicable to such machines, whether they are employed for converting mechanical power into an electric current, which current may be used either for lighting or plating, or other purposes, or whether they are employed conversely for converting an electric current into mechanical power—as, for example, when used for the transmission of power to a distance.

The nature of the invention and its objects will be best understood by reference to the drawings and the following description.

In the drawings, Figure 1 shows the old method of constructing these machines, and Figs. 2 and 3 show my improvements. In Fig. 2 two machines are introduced into the same general circuit, as is done when mechanical power is converted into the current in the first instance, and the current passing through a second machine is reconverted into mechanical power or motion. In Fig. 3 the transmitting-machines are used for lighting purposes, but the general construction and arrangement are the same, except that in Fig. 3 a series of small electric lamps is substituted for the second or receiving-machine, and except that the circuit is completed through a return-wire instead of through earth, as in Fig. 2. The latter variation is however of no importance.

The machines employed may be of any of the well-known forms, except in the arrangement of their wires, hereinafter spoken of, and I have therefore merely indicated the other parts conventionally.

In all the figures C represents a rotating armature of any kind—as, for example, the well-known cylindrical Siemens armature, pro-

vided with a commutator, H, or current-collector, which may also be of any kind, and brushes or metallic strips 1 and 2.

It will be understood by those familiar with magneto-electro machines that a wire circuit or circuits pass around the armature C in such a manner that by its revolution they are made to alternately approach and recede from the poles of a series of electro-magnets, numbered from 3 to 10 in Figs. 1 and 2, and indicated by the letters R and S in Fig. 3. In the latter figure the letter S designates those magnets which are numbered 3, 4, 5, 7, 8, and 9 in Figs. 1 and 2, and the letter R those numbered 6 and 10. The circuit or circuits on the armature lead to the current-collector H in such a manner that when, in any manner, the brushes 1 and 2 are electrically connected the currents induced in the armature-circuits by the rotation of the armature are collected by the brushes and pass through the wire which connects the brushes. It will be understood that although I have applied the word "circuits" to the armature-wires, they do not constitute a complete circuit until connected through the brushes.

My invention relates to the manner of making this connection.

In Fig. 1 it will be seen that a wire is taken from brush 1, passes around the cores of all the electro-magnets of the transmitter to earth, from earth around all of the cores in the receiver to brush 1, and a wire also connects brushes 2 2 of the receiver and transmitter. A complete circuit is therefore established as follows: from brush 1 of the transmitter through its coils to earth; through earth to and through the coils of the receiver to brush 1 of that machine; from brush 1 of the receiver through the commutator and armature circuits to brush 2; through the line to brush 2 of the transmitter, and through the commutator and armature circuits of that machine to brush 1, completing the circuit.

Figs. 2 and 3 show my method of constructing and arranging the wire connections; Fig. 2, as in Fig. 1, for transmitting power, and Fig. 3, which is substantially the same arrangement, for lighting purposes. In these arrangements the line-wire passes directly from brush 1 of the transmitter to the receiver or lamps, just as it passed directly between brushes 2 2 in

Fig. 1; but from the other brush, in my arrangement, the wire, instead of passing through all the coils of the electro-magnets to earth, as before, passes through only a portion of them, 5 as coils 6 and 10, Fig. 2, or coil R, Fig. 3. The main circuit, therefore, passes as follows: from brush 2 of the transmitter through coils 10 and 6 or R to earth, and through earth or second line-wire to and through receiver or 10 lamps to brush 1 of the transmitter, and is completed through commutator and armature, as before. The other coils, 3, 4, 5, 7, 8, and 9, in Fig. 2, or S in Fig. 3, are placed in a shunt-circuit taken from the line at, say, the point 15 marked 20, and returning to it at the point marked 19. The receiving-instrument may, but need not necessarily, be similarly arranged, and is so shown in the drawings.

It will be seen that in Fig. 1 there is but one 20 circuit, and the result is that if this be broken at any point the current must entirely cease. The armature will therefore revolve without doing any duty, the entire load being thus taken off the motive power, which is liable to 25 injure itself and the machine by racing. In my arrangement, however, if either the main or shunt circuit be broken the current will pass through the other circuit magnetizing a portion of the coils, and by accumulation of magnetism absorbing any dangerous excess of 30 power in the machines. If the machine be short-circuited—that is, if accidental connection be made between the wires—say between the points 1 and earth, or the return-line, such 35 connection offering little or no resistance, the entire current would pass through it in preference to the shunt. It must, however, in such case pass through coils 10 and 6, or R, and again by accumulation of magnetism will absorb 40 the surplus power. I have found also by actual tests that in this arrangement there is a great saving of power, and that there is also a very marked absorption of fluctuations in the power by the machine itself, instead of 45 their appearance in the outer or line circuit, injuring the constancy of the work done. These effects will be readily understood by electricians, and inasmuch as their explanation depends purely on theoretical considerations I 50 do not find it necessary to explain them here, sufficient having been said to enable those skilled in the art to make and use machines according to my invention. It will also be understood that the number of coils in the main and 55 shunt circuits can be varied indefinitely, both absolutely and relatively to one another, according to the work required of the machines, their

relative resistances being properly adjusted. Also, the coils in each circuit may be connected among themselves in any desired manner. 60

In an application for Letters Patent already on file in the Patent Office I have described an arrangement in which all the cores of the field-of-force magnets are placed in the shunt-circuit. The hereinbefore-described invention 65 differs from that, however, in the fact that the cores are divided and a part placed in the coils of the shunt-circuit, and a part placed in those of the main circuit, and it is in this division that I believe lies the principle of the invention which I wish to protect in these Letters Patent. The shunt and main circuit coils might also be made to surround the same cores, but such an arrangement would not necessarily produce the effects which are accomplished by 75 the one above described, and I wish it, therefore, to be distinctly understood that it is an essential feature of this invention that the shunt-circuit surrounds and actuates some of the field-of-force magnets which are not in the main circuit, while others of the field-of-force magnets are in the main circuit, and not in the shunt.

In Fig. 3 the numbers 21, 22, and 23 designate a series of lights placed in a series of taps 85 or shunts between two main lines constituting a circuit, which includes one of my machines used as a transmitter, this being the usual manner of arranging a succession of lights to be worked by a common current. Of course an 90 electrolytic bath or other work to be done might be introduced into the circuit in the same or any equivalent manner.

By the term "field-of-force magnets," which I use in this specification, I mean those magnets 95 which, being actuated by the current created by the machine, are themselves used to excite the current in the circuits of the armatures.

What I claim, and desire to secure by Letters Patent, is—

1. A dynamo-electric machine in which the cores of some of the field-of-force magnets are placed in the shunt-circuit only, and the rest of the cores are in the main circuit, substantially as described. 100

2. The method of working dynamo-electric machines, which consists in magnetizing a part of the field-of-force magnets by the main current and a part of them by the current of a shunt-circuit, substantially as described. 105
